Term of patent 14 years

(Cl. D90—20)

FIG. 1

Des. 177,655

PAGE 2

FIG. 3

Figure 1 is a perspective view of an automobile tire showing my new design;

Figure 2 is a cross-sectional view thereof shown on an enlarged scale; and

Figure 3 is a fragmentary front view thereof shown on an enlarged scale.

The characteristic feature of my design resides in the configuration appearance of the side wall portion.

I claim:

The ornamental design for an automobile tire, as shown and described.
